CLAIM

The ornamental design for a adhesive curing pen, as shown and described.

DESCRIPTION

FIG. 1 is a top perspective view of the adhesive curing pen showing my new design;

FIG. 2 is a perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top elevational view thereof; and,

FIG. 8 is a bottom elevational view thereof.

The broken lines in the figures illustrate portions of the adhesive curing pen that form no part of the claimed design.

1 Claim, 8 Drawing Sheets
